AIR CLEANER FOR AUTOMOTIVE VEHICLES

Kenneth F. Russell, Claremont, Calif., assignor to
Herman H. Garner, Claremont, Calif.

Application April 23, 1951, Serial No. 222,373

16 Claims (Cl. 183—15)

1

This invention relates to air cleaners and, more particularly, to those of the oil bath type which are employed, for example, upon internal combustion engines to filter and clean air laden with dust and foreign particles prior to its being passed to the carburetors of the engines.

It is often a practice to employ air cleaners for trucks upon the outside of the cowls a flexible hose leading the cleaned air to the engines. Such trucks operate in all types of weather, and it is therefore important to provide efficient means for excluding rain. Various caps have been attempted for the purpose of adequately deflecting water from the air intakes of cleaners of the indicated type, but heretofore none have been entirely satisfactory.

It is therefore an object of this invention to provide air cleaners with air intakes which will effectively exclude rain, water or melted snow, from entering the air intake of air cleaners, especially cleaners of the type employed upon all-weather trucks.

An incidental object of the invention is to provide guard means presenting a laterally directed channel arrangement which will cause falling water to be directed rearwardly on a forwardly moving truck so that the water will pass to the rear and be caused to drop off rearward of the air intake zone.

A further object of the invention is to provide an air cleaner with an air intake at the bottom and a rain guard so located with respect to the air intake as to deflect rain therefrom and another object is so to space a water-gathering portion of the rain guard with respect to the air intake that air velocities are controlled so as to discharge falling water beyond any zone where entering air can pick up water particles.

It is also an object of the invention to provide an air cleaner possessing efficient air cleaning characteristics in which the air intake is provided at the bottom of the cleaner, rain deflecting means being arranged with respect to the air intake so that water is caught up at the front and sides of the cleaner when used on a forwardly moving truck and discharged at the rear of the cleaner in a manner to avoid falling of the accumulated water in such a zone as to be picked up by air entering the cleaner under suction of the engine.

Another object of the invention is to provide a novel and efficient oil-bath cleaner having a bottom air intake.

Other objects of the invention and the various features thereof will become apparent to those

skilled in this art, upon reference to the following specification and accompanying drawings wherein one embodiment is illustrated.

In the drawing:

Fig. 1 is a vertical cross section through an air cleaner adapted to be employed upon trucks, the view being taken on the line 1—1 of Fig. 2, the cleaner embodying the improved features hereof;

Fig. 2 is a side elevation taken from the left of Fig. 1; and

Fig. 3 is an enlarged vertical sectional detail as indicated by the line 3—3 of Fig. 1.

The form of the invention illustrated includes an upper filter section generally indicated at A and a lower oil cup and air intake section generally indicated at B. The filter section comprises an outer main casing 10 of generally cylindrical construction which houses a filter mass constituting a filter pack 12. The main casing 10 is formed with a top wall 14, and in the upper portion of the casing there is provided a sloping lattice or screen means 15 which confines the upper portion of the filter pack 12. There is thus provided between the generally horizontal top 14 and the screen means 15 a tapering chamber 16 which discharges cleaned air at its deepest side into a laterally disposed outlet neck 17. An angularly directed deflector 18 is disposed across that portion of the lattice or screen means 15 adjacent the outlet neck 17 so as to insure travel of air through the body of the filter pack 12, rather than to permit it to bypass the more remote portion and travel directly to the neck 17.

Located axially within the casing 10 at the lower side of the filter pack 12 there is provided an inverted, generally conical baffle and bottom wall 20 which serves both to support the filter pack 12 and to deflect upwardly moving incoming air which enters through an air inlet neck or tube 22 axially disposed with respect to the main casing 10. The tube 22 is carried on a flared or frusto-conical downward extension 23 of the tube 22, the bottom annular portion of such extension 23 being secured upon an annular bottom wall 24 of a lower, upstanding, cylindrical member 25 constituting the oil cup of the section B. The cylindrical cup member 25 is integral with an upper, cylindrical wall member 26, these members being integrally connected by a horizontally disposed shoulder 27. The upper cylindrical member 26 is secured to the lower end of the main casing 10 through sealed ann

nular joint means generally indicated at 28, as presently to be described in detail.

The conical baffle and bottom wall 20 is carried by an annular slotted or perforated supporting wall 30 which is frusto-conical in shape and slopes downward toward the axis of the main casing 10. This supporting wall 30 is contacted by the conical bottom wall 20 in the form of an annular welded joint 31 below which there depends from the supporting wall 30 an integral inner, cylindrical baffle flange 32. At its outer and upper edge the supporting wall 30 is supported with a down-turned, integral, outer, cylindrical flange 33, concentric with the flange 32 and tightly seated within the lower end of the main casing 10 as by welding. By these means the conical bottom wall 20 below the filter pack 12 is fixedly positioned in operative relationship. For the purpose of properly retaining the materials of the filter pack 12, the upper side of the supporting wall 30 carries suitable screen means 34 which may be in the form of one or more woven wire screens or perforated plate-like members.

Disposed immediately below the slotted or perforated supporting wall 30 is a removable prefilter element generally indicated at 35 which includes an inner depending circular baffle flange 36 within and extending below the cylindrical flange 32. At the top of the cylindrical flange 36 there is integrally provided a frusto-conical slotted annulus 38 corresponding generally with the slotted supporting wall 30, the outer edge of the annulus 38 being provided with a dependent, concentric, outer flange 39 which extends below the previously mentioned concentric, outer flange 33 of the supporting wall 30. In the bottom of the cage provided by the cylindrical flanges 36 and 39 and the frusto-conical annulus 38 there is fitted a bottom member 40 which also is frusto-conical and slotted, this member having short depending flanges 41 at its inner and outer edges which are securely fitted within the depending cylindrical flanges 36 and 39 and fixed in position by welding or otherwise as required. Within the cage thus provided there is placed a body of filtering material 42 constituting a prefilter pack, and upper and lower screens 43 and 44, similar to the screen 34, are used to retain such filter pack.

Carried upon the shoulder 27 between the cylindrical cup and wall members 25 and 26 of the oil cup section is a barrier plate 45 of annular shape whose inner portion is flat and is connected by a sloping annular section 46 with a horizontal annular portion 47 which rests upon the shoulder 27 and may in turn have an upstanding, shallow flange 48 engaging the adjacent inner wall of the member 26. The inner edge of the barrier plate 45 is provided with a series of notches 52 through which oil passes upward during operation of the device, and the seated portion 47 of the barrier plate 45 is provided with an annular series of openings 50 through which circulating oil returns to an oil chamber 53 below the plate 45.

For the purpose of retaining the barrier plate 45 down in its operative position on its annular shoulder 27 at the top of the oil cup member 25 and for retaining the prefilter 35 elevated in the indicated position beneath the annular supporting wall 30, a plurality of springs 54, Fig. 1, is employed, these springs being disposed about vertical legs or pins 55 carried as spaced, opposed pairs depending from short horizontal supporting

bars 56 which engage under the lower edges of the outer cylindrical flange 39 and the adjacent shallow flange 41 of the bottom member 40. Conveniently, each pair of pins 55 and their bar 56 are provided by an inverted U-shaped member whose lower pin ends depend through small openings in the barrier plate 45 at the points where the lower ends of the springs 54 bear. Thus, when the parts are assembled as indicated and the upper edge of the cylindrical wall member 26 is placed in operative engagement with the lower end of the main casing 10 to form the joint 28, the springs 54 are compressed somewhat, thereby serving to press the barrier plate 45 down and working through their bars 56 to hold the prefilter 35 up.

Located on the bottom wall 24 of the oil cup member 25, there is provided a rain guard or deflector generally indicated at 60 which includes a horizontally disposed, outwardly directed, annular, outer flange 62 which is connected with the bottom wall 24 of the cup member 25 by an upstanding, annular, spacing wall 63 which forms an outwardly facing annular groove 64 adapted to collect and deflect rain water. The upper edge of the spacing wall 63 is integrally joined with an annular, horizontal, cross wall 65 secured as by spot welding to the bottom wall 24 of the oil cup and provided at its inner edge with a depending annular flange 66 whose lower edge is approximately level with the horizontal, outer flange 62. The upstanding wall 63 and the depending flange 66 thus provide between them a downwardly faced, annular channel space 68 which functions to control air velocities adjacent the air intake, as presently to be described.

By these structural arrangements, the inner depending flange 66 of the rain guard 60 and the frusto-conical extension 23 provide a mouth 70 which receives incoming air entering under suction influences of the engine to which cleaned air is being supplied. Such entering air passes from the mouth 70 into a throat 72 formed by the centrally disposed air inlet tube 22, the entering air continuing into an enlarged chamber 73 which may be termed an expansion chamber and is located directly below the conical baffle or bottom wall 20. From the expansion chamber 73 the entering air passes downward between an in-turned flange 74 at the top of the inlet tube 22 and an in-turned sloping flange 75 which is integral with the lower portion of the conical baffle or bottom wall 20, and into an annular chamber 76 around the tube 22 and within the depending cylindrical flanges 32 and 36. The normal oil level usually is at the level of the horizontal portion 47 of the barrier plate 45 which is the same level as that of the lower edges of the cylindrical, depending flange 36 and the adjacent flange 41 of the bottom member 40 of the prefilter 35. In operation this oil level is depressed above the barrier 45 to provide an air-washing and oil-entrainment chamber 77, whence the oil-laden air passes upward into an annular zone 78 which acts as an oil return zone.

When the device is being prepared for use, the oil chamber 53 below the barrier plate 45 and the oil-entrainment space 77 thereabove are filled with oil to bring it up to the level of the horizontal portion 47 of the barrier plate, which level is also indicated at 80. With the prefilter 35 supported in position upon the springs 54, as above described, the upper portion of the cylindrical wall member 26 of the oil cup section is attached to the lower end of the main casing 10 by being

engaged about the lower edge portion of the concentric, outer, annular flange 33 of the supporting wall 30. To effect a seal, the upper edge of the wall member 26 is provided with an outwardly rolled and down-turned flange 85 which abuts against an annular rubber or other appropriate packing member 86 carried within an out-turned, downwardly directed, annular flange 88 formed integrally with the lower end of the main casing 10. Above the outwardly directed flange 88 there is secured about the casing 10 a band 90 having its ends secured together as by a small bolt 91 and provided at opposite sides with ears 92 each receiving the looped end 93 of an eye bolt or rod 94 threaded at its lower end 95 to receive a thumb nut 96 engageable under a bracket 98 welded to the outer side wall of the lower cup member 25. By these means, when the thumb nuts 96 are swung under their brackets 98 and screwed up tight, the packing 86 is compressed and the parts are drawn up tight in proper position to produce the previously mentioned sealed joint 28.

When the bottom-feed air cleaner of this invention is in operation on a truck in the rain, rain striking the outer wall of the upper filter section A and the oil cup and air intake section B runs down the surface thereof under the influence of gravity, such downward movement having also a horizontal component when the truck is in motion. In general, it is the exclusion of rain from the air intake when the truck is traveling that constitutes the principal problem. With the present structure it is important to have an outer edge such as provided at the periphery of the horizontal flange 62 of the rain guard 60, such edge being indicated at C in Fig. 3. It is also important to locate the lower edge of the inner depending flange 66 indicated at D at an appreciable distance from the edge C, because the edge D is disposed at the region of highest velocity of the entering air. The annular groove 64 is required to conduct rain water from the forward portion of the apparatus rearward to places of discharge as the truck moves forward. However, it is equally important to provide the downwardly opening annular channel space 68 between the spacing wall 63 of the rain guard 60 and the depending flange 66. This is because this annular space or channel 68 acts further to reduce the velocity of the air at the edge C. The optimum position for the lower edge D of the depending flange 66 is slightly above the level of the horizontal flange 62, as best seen in Fig. 3. However, it may satisfactorily be lowered to be in line with the under face of the flange 62. Preferably it should not be brought farther down with respect to the flange 62 because such lower edge D of the flange 66 would then be too close to the path of water dropping from edge portions at C of the flange 62. The path of such dropping water when the truck is in motion is generally indicated by the broken arrow E in Fig. 3. Such angular path of the dropping water is produced by the resultant air currents whose effectiveness is in the direction of the arrows F directed toward the right, during travel of the truck in a direction toward the left as viewed in Fig. 3.

Again, if the lower edge of the flange 66 represented by the letter D is raised substantially above the position indicated, then the pressure at the junction between the flange 62 and the upstanding wall 63, which is indicated at G, is so lowered that the horizontal velocity of air at the point C is unduly increased and results

in the raising of the path of the water dropping from the edge of the flange 62 as represented by the broken arrow E previously mentioned. Increased heights of the groove 64 of the channel 68 may be used, although with the particular dimensions described above no appreciable improvement in the stated factors is produced by height increase. Of course, the bulk of the rain working down the walls of the apparatus to the rain guard 60 passes into the annular groove 64 and is carried therethrough toward the rear of the flange 62 whence it is discharged clear of air entering the air-intake mouth 70 within the depending annular flange 66. As a consequence, rain has been effectively excluded from the entering air, even with maximum air-intake velocities and under maximum truck speed. The channel 68 reduces air velocity at both edges C and G and stops inward water flow along the under face of the flange 62. In actual practice a completely effective apparatus has an air inlet diameter determined by the air inlet tube 22 of 4½ inches, the over-all diameter of the oil casing 10 being about 12 inches, the over-all diameter of the oil cup member 25 being about 11¾ inches, the cross-sectional width of the rain guard 60 on any radius between the depending flange 66 and the outer edge of the horizontal flange 62 being about 2 inches, and the depth of the groove 64 being about or just over ½ inch, which is also approximately the depth of the annular channel 68. In such construction, the entrance to the mouth 70 of the air-intake, as defined by the diameter of the depending annular flange 66, is slightly less than 3 inches or about 7½ inches. It is obvious that this diameter of the annular flange 66 determines the relative horizontal spacing between the previously described edges C and D of the flanges 62 and 66. While it is desirable to have the mentioned diameter as great as possible to reduce air-intake velocity, it is also important to have such diameter small enough for the water dropping off of the forward point of the edge C to fall far enough to avoid the region of high air velocity adjacent the corresponding point D. While the dimensions given represent a practical construction, they are, of course, not too critical, but in general the diameter of the entrance to the mouth 70 across the depending annular flange 66 is about two-thirds of the over-all diameter of the cleaner, or between about 60% and 70% of such over-all diameter.

The path of the air flow upward into the cleaner, as has been indicated above, is through the mouth 70 and the throat 72 into the expansion chamber 73, the air passing radially outward and being deflected downward by the sloping wall of the conical baffle or bottom wall 20. As the air passes between the rolled flange 74 on the top of the air inlet tube 22 and the inward and downwardly sloping flange 75 on the lower edge of the bottom wall 20, the flange 75 diverts the entering air inward, reduces the turbulence in the annular chamber 76 immediately therebelow, and tends to lower the air velocity. Without the flange 75 the air would crowd the walls provided by the depending concentric flanges 32 and 36 to produce excessive turbulence at the lower edge of the flange 36 and interfere with passage of air to the prefilter 35. The rolled flange 74 functions to reduce air restriction in the passage lying between the tube 22 and the sloping flange 75.

As the moving air passes down through the

annular chamber 76, it depresses the oil level, whose normal position is indicated at 80, so that such traveling air entrains a quantity of oil in the entrainment zone 77 and deflects it laterally under the lower edge of the depending annular flange 36 of the prefilter 35. This sudden change in direction of the air causes the dust or other foreign matter in the air to be thrown against the upper surface of the now exposed barrier plate 45 where it is entrapped by impingement upon the oil-wetted surface. The air and entrained oil are then deflected to the filters where the oil thoroughly wets the filter mass comprising the pack 42, its oil-wetted surfaces also entrapping any dust or other foreign matter still retained by the air. The path of the air is generally indicated by the arrows in Fig. 3 which indicate that movement continues upward from the prefilter 35 into the main filter pack 12 above the conical baffle or bottom wall 20. The air passing into this filter pack 12 also thoroughly wets the mass of filtering material with the result that an oil excess accumulates which returns to the prefilter 35 in a direction somewhat as indicated by the return arrows, this excess oil continuing into the oil return space 78 below the prefilter 35 and thence downward through the oil return openings 50 at the edge of the barrier plate 45 into the oil chamber 53. Similarly, oil is caused to sweep along the upper face of the plate 45, and this oil laden with dust picked up by impingement also passes through the return openings 50 and down into the oil chamber 53. In the chamber 53 there is sufficient quiescence for dust particles to settle out of the oil which then, due to the oil head established at the return openings 50, moves upward through the notches 52 at the inner edge of the barrier plate 45. In the indicated manner oil is constantly circulated into the filter pack 12 and returned therefrom, the cleaned air passing upward through the screen means 15 to the outlet neck 17, and the dirty wash oil returning, as stated, by way of the return openings 50 in the plate 45 to the oil chamber 53 which constitutes a separating chamber.

From the foregoing it is apparent that highly efficient means are provided for excluding rain from an air cleaner which operates out in the weather, and at the same time for cleaning the entering air by oil-bath removal of dust and other foreign elements which may be contained in the air. It will be appreciated also that, by causing entrance of the air through the bottom of the air cleaner and below the bottom wall 20 of the main casing 10, the cross-sectional area of the filter pack 12 in the casing 10 is very much greater than the cross sectional area of the annular prefilter 35.

As a consequence, adequate, low-pressure areas are provided above such bottom wall 20 and along the side wall of the casing 10 to provide for proper return of dust-laden washing oil carried into the filter pack 12 by the moving air. This arrangement also makes it possible to reduce the height of the apparatus, and more particularly the filter pack 12 because of the disposition of the air inlet within the oil cup. Even with this arrangement, the oil cup holds adequate oil to provide for proper wetting of the filter pack elements and return of the oil for separation of solid particles in the oil chamber 53. At the same time I avoid provision of a special water-excluding cap required with cleaners which are to be exposed to the elements and which receive

their air through upper portions of the cleaner.

I claim as my invention:

1. In combination in an oil-bath air cleaner: an upper casing enclosing a filter pack and having a bottom wall supporting said pack; an oil-cup device at the lower end of said casing having a lower wall and having a central upstanding air tube means supported by said lower wall of said oil-cup device and providing an air-intake passage extending through said oil-cup device for directing entering air against said bottom wall; baffle means extending downward from said bottom wall and around said air tube means and providing a free lower edge within said oil-cup device for the passage of air thereunder, said baffle means providing an outer air passage therearound to receive air passing under said free lower edge; air-passing support means for said filter pack above said outer air passage; and a barrier plate carried within said oil-cup device below said free lower edge and around a lower portion of said air tube means for deflecting upward air descending around said tube means, said barrier plate providing oil-passage means adjacent its inner edge for passage of oil upward adjacent said air tube means and also providing oil-passage means adjacent its periphery for passage of oil downward into the bottom of said oil-cup device and thus providing for oil circulation radially outward above said plate and radially inward below said plate.

2. A combination as in claim 1 including a rain guard means having flange means secured to the bottom of said oil-cup device in spaced relation to such bottom and forming a laterally directed annular groove for gathering and directing away from said air-intake passage water running down the side of said cleaner.

3. A combination as in claim 2 wherein said rain guard means includes a downwardly directed flange disposed around the entrance of said intake passage in inwardly spaced relation to the groove-forming flange means.

4. A combination as in claim 3 wherein the lower edge of the downwardly directed flange of said rain guard means lies approximately at the level of said groove-forming flange means.

5. A combination as in claim 4 wherein a downwardly faced annular channel is provided between said groove-forming flange means and said downwardly directed flange means of said rain guard means to control air velocities in the vicinity of said air-intake passage.

6. A combination as in claim 1 including spring means disposed between said barrier plate and said air-passing support means to hold said barrier plate down in position in said oil-cup device.

7. A combination as in claim 6 including an annular prefilter device disposed below said air-passing support means and around said downwardly extending baffle means, said spring means being disposed below said prefilter means.

8. In combination in a rain-excluding air cleaner: an upper casing enclosing a filter pack and having a bottom wall means supporting said pack; an oil-cup device carried at the lower end of said upper casing and having a central, upstanding air-intake tube which directs entering air against a central portion of said bottom wall means, said air tube providing a downwardly opening air inlet; and rain guard means disposed around said air inlet to exclude water from said inlet, said rain guard means including annular flange means secured to the bottom of said oil-cup device and having a laterally directed

flange ring forming a laterally and outwardly directed water-receiving groove through which rain will pass horizontally from one side toward the opposite side as the structure is moved horizontally.

9. A combination as in claim 8 including an annular, inner, depending flange means disposed approximately at the edge of said air inlet and spaced inwardly from the outer edge of said angular, groove-forming flange means.

10. A combination as in claim 9 wherein a downwardly facing annular groove is provided between said depending flange means and said groove-forming flange means.

11. A combination as in claim 10 wherein the bottom of said downwardly facing annular groove and the lower edge of said depending annular flange are disposed approximately at the level of the lowermost portion of the said groove-forming flange means.

12. In combination in a rain-excluding air cleaner: an upper casing enclosing a filter; an oil-cup device at the lower end of said casing; air inlet means for supplying air to be cleaned to a zone below said filter and above said oil-cup device; and rain guard means disposed about said air inlet means and including horizontal, outwardly directed flange means forming a horizontal, outwardly directed groove extending around said air inlet means to receive water running down the side of said cleaner and dis-

charge such received water laterally in a region beyond said inlet means.

13. A combination as in claim 12 including means providing an annular downwardly facing channel within said groove-forming means to control the velocity of air passing beneath said groove-forming means and channel to said inlet means.

14. A combination as in claim 13 including a
10 depending inner flange about said inlet means
and spaced inward from said groove-forming
means to control the velocity of air passing
through said inlet means.

15. A combination as in claim 12 wherein said inlet means extends upward from the bottom of said oil-cup device.

16. A combination as in claim 12 including a depending inner flange disposed about said inlet means and spaced inward from said groove-forming means and depending below the adjacent bottom portion of said oil-cup device to provide a free lower edge approximately at the level of said horizontally directed flange.

KENNETH F. RUSSELL.
